UNITED STATES PATENT OFFICE

150,127

DESIGN FOR COMBINED BRACELET AND WATCH CASING

Markus Geduldig, New York, N. Y.

Application January 18, 1947, Serial No. 136,225

Term of patent 3½ years

(Cl. D42—8)

To all whom it may concern:

Be it known that I, Markus Geduldig, a citizen of the United States of America and residing in the city, county, and State of New York, have invented a new, original, and ornamental Design for a Bracelet and Watch Casing, of which the following is a specification, reference being made to the accompanying drawing, forming a part thereof.

Fig. 1 is a top plan view of the combined bracelet and watch casing showing my new design.

Fig. 2 is a bottom plan view of the combined bracelet and watch casing as illustrated in Fig. 1.

Fig. 3 is an edge view of the combined bracelet with watch casing as seen from below of the showing of Fig. 1.

The links of the bracelet shown in full lines are repeated throughout the length of the bracelet as indicated by the broken line showing.

I claim:

The ornamental design for a combined bracelet and watch casing, substantially as shown and described.

MARKUS GEDULDIG.
